corporation of Delaware

Application March 5, 1940, Serial No. 322,296
In the Netherlands April 11, 1939

3 Claims. (Cl. 250—20)

This invention relates to a wireless receiver provided with automatic tuning correction and automatic gain control, the time constant of the automatic tuning correction being greater than the time constant of the automatic gain control.

A wireless receiver of this kind can be used conveniently with short wave reception. Short waves are subject to fading as are also the waves situated in the medium-wave band. The fading occurring with short waves is, however, differentiated from the fading in the medium-wave band by the fact that the receiving intensity with short waves may vary very rapidly, say 25 times and more per second. In addition, with short-wave reception so-called selective fading may occur. The phrase "selective fading" is to be understood to define a fading which only occurs in a narrow frequency band at one time. If the amplification of the receiver has to be controlled automatically in synchronism with the fading the time constant of the automatic gain control must be chosen to be so small that even with very rapid fading sufficiently rapid control occurs. This time constant may be about $\frac{1}{25}$ sec.

Selective fading presents difficulties when the carrier wave to be received is just comprised in the narrow frequency band in which selective fading occurs, since in this case the carrier wave is received with greater weakness compared with the side bands so that the chance of over-modulation is very great. To remove or reduce this defect in the receiver it is known to amplify the carrier wave to a greater extent than the side bands. For this purpose in the receiver the frequency band to be detected is fed to a sharp bandpass filter, for example a crystal, the side bands being thus suppressed to a greater extent than the carrier wave.

In addition, provision must be made for the receiver frequency band to be located relatively to the pass-range of the crystal so that the carrier-wave frequency lies in the middle of the said range, since the crystal is so sharp that in the case of small divergences from the correct frequency the amplitude of the carrier wave decreases to such an extent that overmodulation occurs nevertheless. Such a receiver should, therefore, be provided with automatic tuning correction. In a system of automatic tuning correction involving the use of filters having pass-ranges on either side of the frequency constancy of which is to be maintained, these filters, in order that they may be capable of operating efficiently, must be as sharp as the filter by which the carrier wave is filtered. In this form of auto-

matic tuning correction the receiver becomes, therefore, comparatively expensive.

Hence, use is preferably made of a system of automatic tuning correction in which fewer filters are required, and, for example, of a system based on phase differences between the carrier wave present in the modulated signal and the carrier wave filtered from this signal which depend on the tuning of the receiver. This is done because in this case the sharp filter already present can be made use of. In such a circuit arrangement, depending on phase differences, for automatic tuning correction overmodulation, and the consequent reversal to the extent of 180° of the phase of the modulated carrier wave, is, however, responsible for the control voltage which is supplied upon incorrect tuning changing its polarity periodically. Thus, the disadvantage arises that the receiver is adjusted still farther away from the correct tuning point during these moments and this occurs very rapidly, because the control voltage instead of decreasing as in the case of normal tuning correction increases during detuning.

For the purpose of eliminating the said difficulty, that part of the circuit that governs the time which elapses between the variation of the frequency, constancy of which is to be maintained, and the correction of this frequency may be proportioned so as to be possessed of a time constant of at least two seconds whereby the chance of any change of the polarity of the control voltage is very small.

When fading occurs in these circumstances the amplification of the receiver is controlled in synchronism. The anode current of the controlled tubes thus varies in synchronism with the fading and this is responsible for the supply voltage varying in an identical manner at the terminals of the direct current supply source of the receiver. This varying supply voltage is responsible in turn for a frequency modulation in synchronism with the fading of the frequency set up by one or more oscillators present in the receiver. The carrier wave to be filtered by the crystal is thus displaced in the same rhythm relatively to the pass-range of the crystal. In the case of rapid fading this gives rise to difficulties since the rapid displacement cannot be compensated by the automatic tuning correction, because the latter has too great a time constant for this for the reasons set out above.

The invention has for its object to retard such rapid frequency modulation, and according to the invention this is insured by the supply volt-

ages, which upon alteration lead to variation in frequency of one or more local oscillators, being stabilized by means of a quick-acting stabilizing device.

Stabilizing of the supply voltages is preferably effected by means of one or more gas discharge tubes. It would, also, be possible to maintain sufficient constancy of the supply voltages by choosing the time constant of the smoothing filter of the direct current supply source to be much greater than the time constant of the automatic tuning correction. This solution is, however, costly, and requires much space. In a system of automatic tuning correction a change in frequency of one or more local oscillators is brought about by means of a control voltage which is derived from the divergence from a frequency of the requisite value. This may be effected conveniently by the gain of a discharge tube, connected as a reactance in parallel with an oscillator circuit, being determined by means of the said control voltage, and the value of the said reactance being a function of the gain of the said tube. The gain of this tube is, however, also dependent on one or more supply voltages fed to it, and for these reasons the supply voltages are stabilized according to a further feature of the invention.

In addition, variations in the supply voltages fed to one or more oscillator valves will generally bring about variations in frequency so that it is advisable also to stabilize these supply voltages.

In order that the invention may be clearly understood and readily carried into effect it will now be described more fully with reference to the accompanying drawing. This drawing shows a diagram of connections of a wireless receiver, constructed according to the invention, provided with automatic tuning correction and automatic gain control, the time constant of the automatic tuning correction being greater than the time constant of the automatic gain control. The signal frequency received by means of an antenna 1 is fed to a mixing valve 2 which is coupled to a separate oscillator tube 3. The intermediate frequency set up in the mixing valve 2 is chosen to be high in view of image frequencies that may occur, and is fed to a second mixing valve 6 with the interposition of a bandpass filter 4 and an oscillatory circuit 5. The mixing valve 6 converts the high intermediate frequency into a low one. The oscillatory circuit 5 is tuned to the image frequency of the first intermediate frequency relatively to the second oscillator frequency. The two grids 7 and 8 of the mixing valve 6 which are nearest to the cathode act respectively as the control grid and the anode of the second local oscillator which comprises an oscillator circuit 9.

The oscillator circuit 9 has connected in parallel therewith the cathode-anode impedance of the discharge tube 10; the control grid 11 of which has fed to it, with the interposition of a phase shifting network constituted by condensers 12 and 13 and a resistance 14, voltage obtained from the voltage occurring across the oscillatory circuit 9 but about 90° out of phase therewith. The anode current of the tube 10 is in phase with the grid voltage, and consequently also about 90° out of phase with the anode voltage. Thus, the tube 10 behaves as a reactance which is connected in parallel with the oscillator circuit 9, and whose value depends on the gain of the tube 10.

The gain is governed not only by the value of

the supply voltages of the tube 10, but also by the bias supplied to the control grid 11. The variation of the amplification of tube 10 is, therefore, responsible for a variation of the oscillator frequency, and thus of the intermediate frequency produced by the mixing valve 6. This intermediate frequency is low, and, with the interposition of an oscillatory circuit 15 tuned to this frequency and included in the anode circuit of the mixing valve 6, is fed to an inductance coil 16 grounded at the middle point, to an oscillatory circuit 17, and to one of the diode anodes 18 of a duo-diode 19.

The inductance coil 16 supplies voltage to a crystal 20 and, in phase-opposition, an equally high voltage to a condenser 21 which serves to neutralize the natural capacity of the crystal. Two resistances 22 and 23 in parallel with the halves of the coil 16 and a resistance 24, between the connecting point of the crystal 20 and the condenser 21, serve to lessen the damping which the crystal experiences from the circuit 15. The other terminal of the crystal 20 is connected to the control grid of an amplifier valve 25 and, with the interposition of an inductance coil 26, to ground. The anode circuit of the amplifier valve 25 includes a phase shifting network constituted by an inductance coil 27 in series with a variable resistance 28 which is shunted by a condenser 29. The anode of the amplifier 25 is connected to the midpoint of the inductance coil 30 of the oscillatory circuit 17 with the interposition of a condenser.

The ends of the oscillatory circuit 17 are connected to the anodes of two diodes enclosed within a single tube envelope 31. The cathodes of these diodes are connected by the series combination of two resistances 32 and 33, the connecting point of which is connected to the middle point of the coil 30. One of these cathodes is grounded. The other cathode is grounded with the interposition of a condenser 34, and connected to the control grid 11 of the discharge tube 10 by a conductor 35 and a resistance 14. Upon attainment of entirely correct tuning the phase relation of the amplified carrier wave and the modulated carrier wave which is transmitted to the circuit 17 by induction is such that there is no potential difference between the two cathodes of the diode 31. If, however, the intermediate frequency in the circuit 15 varies, a positive or a negative control voltage is set up which brings about such variation of the reactance formed by the discharge tube 10 that tuning is corrected automatically. The time constant of the automatic tuning correction is substantially governed by the values of the condenser 34 and of the resistances 32 and 33 and preferably amounts to at least 2 seconds. The lead 35 is designated "AFC".

In the diode formed by the diode anode 18 and the cathode of the valve 19 detection of the voltage across the circuit 15 occurs. The anode current of the valve 19 is controlled by means of the unidirectional voltage obtained. The cathode of this valve is connected by a resistance 41 to a point 37 of negative potential relative to ground.

The valve 19 includes a further diode anode 36 which, with the interposition of a series combination of two resistances 38 and 39, is connected to a point 40 of lower negative potential relative to ground than the point 37. So long as the grid voltage of the valve 19 is zero the cathode is more positive than the diode anode 36, since a higher voltage drop occurs across the re-

sistance 41. When detection of the voltage across the circuit 15 occurs the anode current of the valve 19 decreases, and the cathode falls in potential until the path of the diode anode 36 becomes conductive. At this moment the negative voltage of the diode anode 36 which was constant hitherto starts to become more negative. With the interposition of a filter constituted by a condenser 42 and a resistance 43, the voltage of the diode anode 36 is fed to one or more preceding valves (in the drawing to the valve 6 only) for the purpose of controlling the amplification. This is the automatic gain control (A. G. C.) circuit. The point of connection between the resistances 38 and 39 is connected by a similar R-C filter to a conductor 44 which feeds control voltage to a tuning indicator not shown in detail on the drawing. The time constant of the automatic gain control which is governed by the resistances and condensers included in the circuit is low in view of rapid fading, and amounts, for example, to $\frac{1}{25}$ sec.

The oscillations received from the crystal 20 which are constituted by an intermediate frequency carrier wave with side bands becoming feebler towards the high modulation frequencies are transmitted to the oscillatory circuit 45 by the coil 26, after which detection occurs between a diode anode 46 and the cathode of an amplifier valve 47, in which a diode is incorporated. The detected oscillations are fed to the control grid 48 of the amplifier valve 47, said control grid being connected to ground with the interposition of the parallel combination of a resistance 49 and a series resonance circuit constituted by an inductance coil 50 and a condenser 51 and tuned to the carrier wave frequency. Thus an efficient by-pass is obtained for the carrier wave frequency.

The anode circuit of the anode valve 47 includes a transformer 52 having a low primary impedance so that the anode current of the amplifier valve 47 is not affected thereby as regards its value. The voltage at the terminals of the secondary of the transformer consequently increases with increasing frequency so that the loss of high modulation frequencies in the crystal 20 is compensated. A final amplifier valve 53 connected to the transformer 52 amplifies the low frequency oscillations, and feeds them to a loudspeaker 54.

The receiver comprises a gas-discharge tube 55 which, in series with a resistance 56, is connected between ground and the positive terminal of the direct current supply source. When the voltage of this source fluctuates the voltage across the gas discharge tube 55 stays constant. This constant voltage is supplied to the screening grid 60 of the discharge tube 10, and to the oscillator anode 8 of the mixing valve 6 with the interposition of a low pass filter constituted by two condensers 57, 58 and a resistance 59. The said two electrodes consequently remain at a constant potential and do not lead to variation of the frequency generated. In parallel with the gas discharge tube 55 the resistances 61 and 62 are connected in series. The resistance 61 is a potentiometer, and the sliding contact thereof is connected to the cathode of the discharge tube 10. The current passing through the resistance 61 is maintained constant by the constant voltage of the gas discharge tube 55 so that the fixed grid bias of the tube 10 does not vary either. A further gas discharge tube 63 together with a resistance 64

provides in a similar manner for constancy of the supply voltage of the first oscillator 3 to be maintained.

What is claimed is:

1. In a superheterodyne receiver of the type comprising a signal input circuit, a local oscillator provided with a tuned tank circuit and means for producing intermediate frequency energy from signals and local oscillations, a frequency control tube having at least a cathode, control electrode and anode, means to connect the anode to cathode impedance of the tube across the tank circuit, means to apply to said control electrode alternating voltage in phase quadrature with the tank circuit voltage, and means responsive to departures in frequency of the intermediate frequency energy for controlling the gain of said control tube; the improvement which comprises a source of energizing direct current voltage for the oscillator and control tube, energizing connections from said source to the electrodes of the oscillator and control tube, an automatic gain control circuit arranged to regulate the receiver output in a sense to compensate for carrier fading, said gain control causing frequency modulation effects of said oscillator during rapid fading periods, means to supplement the frequency control of said tank circuit during such periods, said last means comprising a quick-acting stabilizing device electrically connected with said voltage source to maintain said energizing voltages applied to the electrodes of the oscillator and control tube substantially constant.
2. In a superheterodyne receiver of the type comprising a converter tube having a cathode, an oscillator control electrode, an oscillator anode electrode, a signal input electrode and an output electrode, a local oscillator tank circuit coupling the oscillator anode and control electrodes, an intermediate frequency output circuit coupled to said output electrode, an electron discharge tube having its electrodes constructed and arranged to provide a simulated frequency correction reactance across the tank circuit, a relatively slow-acting means responsive to frequency deviation of the intermediate energy from a predetermined frequency value for controlling the gain of the correction tube, a relatively fast-acting means responsive to signal carrier amplitude variations for varying the receiver gain in a sense to overcome the amplitude variations, said last means being connected to said signal input electrode and a source of direct current voltage connected to the electrodes of said converter tube and correction tube; the improvement which includes means to supplement the frequency correction action of said slow-acting means during periods of relatively fast variation of said carrier amplitude, said means comprising a relatively fast-acting voltage stabilizing device operatively associated with said voltage source, and a connection from the stabilizing device to an electrode of said converter tube to prevent frequency modulation effects otherwise caused by the gain control means during said periods.
3. In a superheterodyne receiver of the type comprising a converter tube having a cathode, an oscillator control electrode, an oscillator anode electrode, a signal input electrode and an output electrode, a local oscillator tank circuit coupling the oscillator anode and control electrodes, an intermediate frequency output circuit coupled to said output electrode, an elec-

tron discharge tube having its electrodes constructed and arranged to provide a simulated frequency correction reactance across the tank circuit, a relatively slow-acting means responsive to frequency deviation of the intermediate energy from a predetermined frequency value for controlling the gain of the correction tube, a relatively fast-acting means responsive to signal carrier amplitude variations for varying the receiver gain in a sense to overcome the amplitude variations, said last means being connected to said signal input electrode and a source of direct current voltage connected to the electrodes of said converter tube and correction tube; the

improvement which includes means to supplement the frequency correction action of said slow-acting means during periods of relatively fast variation of said carrier amplitude, said means comprising a relatively fast-acting voltage stabilizing device electrically connected with said voltage source, and a connection from the stabilizing device to an electrode of said converter tube and an electrode of the correction tube to prevent frequency modulation effects otherwise caused by the gain control means during said periods.
